METHOD OF AND APPARATUS FOR
SCORING PAPERWilliam L. Angel and George K. Schray,
Portland, Oreg.

Application July 16, 1935, Serial No. 31,588

5 Claims. (Cl. 101—408)

This invention relates generally to the art of printing, and particularly to a method of and apparatus for scoring paper.

The main object of this invention is the development of a method of and the provision of an apparatus for scoring paper during a printing operation without inking the scoring strip or necessitating a second run of the job.

The second object is to eliminate ink marks on the printed job and to prevent the rollers from touching the scoring rule thereby saving the rollers.

The third object is to leave the printed sheet lying flat on the tympan by preventing the rule from pulling the sheet away.

The fourth object is to permit the use of the standard scoring rule, such as is now in common use.

We accomplish these and other objects in the manner set forth in the following specification as illustrated in the accompanying drawing, in which:

Fig. 1 is a perspective view showing the device in use.

Fig. 2 is a section taken along the line 2—2 in Fig. 1 showing the rollers applying ink to the type.

Fig. 3 is a view similar to Fig. 2 showing the papers moving up to the type.

Fig. 4 is a view similar to Fig. 3 but showing the position of the parts during the printing operation.

Fig. 5 is a section taken along the line 5—5 in Fig. 2.

Fig. 6 is a fragmentary side elevation of a piece of scoring or perforating rule.

Similar numbers of reference refer to similar parts throughout the several views.

In order to illustrate this invention, there is shown a bed 10 of a conventional form of printing press on whose tympan 11 may be placed the paper 12 upon which the printing is to be done. The position of a gripper 13 is also indicated. Type 14 are shown in position on the bed 10 and an inking roller 15 is shown applying ink to the type 14. A perforating or scoring rule 16 is shown in position along side of the type 14.

Referring particularly to our invention, which consists of a barrier composed of an elongated bar 17, along whose edge 18 is mounted a facing strip 19 which is supported on the headed guides 20 which are slidable within the bar 17, the heads 21 limiting the separation of the members 17 and 19. The members 19 are urged by means of the springs 22 which occupy the recesses 23 in the

bar 17. The barrier bar 17 is locked into position next to the perforating rule 16, and although the perforating edge of the rule 16 extends beyond the face of the type 14, the facing strip 19 extends beyond the perforating edge of the rule 16 while ink is being applied to the type 14 by the roller 15.

It will be noted that a gripper 13, which holds the paper 12, is directly in line with the facing strip 19 so that during the printing movement of the tympan 11, the gripper 13 moves the strip 19 out of the way exposing the perforating rule 16 and permitting it to form the rule of perforations within the paper 12. Obviously, when the tympan 11 again moves away from the bed 10, the strip 19 will also move out to the position shown in Fig. 2, so that the next inking operation will not permit the roller 15 to apply ink to the rule 16 or to permit the rule 16 to injure the inking roller 15. It is desirable to provide a gripper 13 which is somewhat narrower than those in common use.

It can be seen from the foregoing that the use of this device involves no change in existing presses, but merely requires the use of the yieldable barrier, such as shown in Fig. 5 of the drawing, and that by the use thereof it is possible to print and perforate a sheet of paper at one movement of the press without the slightest danger of producing ink marks on the printed job or having the printing rollers touch the scoring rule.

We claim:

1. A device of the class described consisting of a scoring rule, a gripper and a spring urged barrier exceeding the height of said scoring rule and adapted to be placed adjacent to said scoring rule in a manner that said barrier shall protect said rule from becoming inked but shall yield sufficiently under the pressure of said gripper during the printing operation to permit said rule to perforate the paper at the same time.

2. In a device of the class described the combination of a scoring rule, a spring urged barrier locked against said scoring rule having sufficient spring tension to prevent the inking rollers from contacting said rule during the inking operation, and a gripper mounted in parallelism with said rule adapted to force said barrier into a rule exposing position during a printing operation.

3. A printing press including a bed, a scoring rule mounted on said bed, a gripper for said bed, a barrier consisting of a bar adapted to be locked up with said scoring strip upon said bed and in parallelism with said gripper, said bar having a yieldable face adapted to protect the scoring

- points of the scoring rule against the ink roller during the inking operation and to be moved by the gripper to a position which will expose said points during the printing operation.
5. In a printing press, the combination of a bed having a tympan and a gripper associated therewith, a spring urged barrier adapted to be locked against a scoring rule together with type upon said bed in register with said gripper, said scoring rule being more than type high and said barrier being higher than said rule but being capable of yielding under pressure of said gripper during the printing operation for the purpose of exposing said scoring rule.
5. A method of scoring paper while printing consisting of protecting the scoring rule against inking during the inking operation and removing said protection during the printing operation.

WILLIAM L. ANGEL.
